UNITED STATES PATENT OFFICE.

THEODOR BUCHHOLZ, OF BERLIN-ZEHLENDORF-WEST, GERMANY.

RAIL FASTENING.

Original application filed January 15, 1926, Serial No. 31,562, and in Germany May 16, 1925. Patent No. 1,640,750, dated August 30, 1927. Divided and this application filed March 15, 1927. Serial No. 175,595.

This invention relates to a rail fastening in which the base of the rail is supported between projections or ribs provided on a sole plate. The invention consists in this, 5 that the ribs extend over the entire length of the sole plate and are provided in the middle with a recess of the width of the shank of a T-bolt for holding down the rail, and the sole plate is provided with a 10 larger opening for the insertion of the T-bolt under the projecting parts of the rib.

A constructional form of the rail fastening according to the invention is illustrated by way of example in the drawing, in which 15 Figure 1 is a vertical section through the rail.

Figure 2 is a plan view of the sole plate. Figure 3 is a perspective view of a detail.

Referring to the drawing, the sole plate 20 α which is fixed on the wooden sleeper c by means of the screws d is provided on either side of the rail i with ribs or projections b of which only that rib situated on the one side of the rail is shown. The 25 rail i is held down on the sole plate α by means of clips h which are drawn down tightly on the sole plate by means of fixing bolts f . Between the ribs b and the base of the rail, gauge adjusting members can 30 be introduced as required.

The ribs or projections b of the sole plate α are made low and extend over the entire length of the sole plate α (this length being measured in the longitudinal direction of the 35 rail). Below the middle part of each rib a downwardly extending aperture y of approximately square shape is formed in the sole plate α , the side of the square corresponding to the length of the heads of the 40 bolts f which hold down the clips h . The ribs b , however, have in their middle only a narrow gap having only the width of the shank of the bolts, so that the parts u of the ribs extend over the corresponding edges 45 of the aperture y of the plate α , and the heads of the bolts which are inserted from the side come to lie under the parts u of the ribs. Each of the clips h , as shown in Figure 3, is provided on the lower edge of 50 the outer limb with a lug w which fits into the aperture y and at the thinner part of the sole plate (which is tapered) extends almost to the sleeper. This lug w has a two-fold advantage, on the one hand it prevents

the clip h from slipping and on the other 55 hand, it fills the part of the aperture y of the sole plate which is not occupied by the head of the bolt f . Consequently the aperture y cannot become filled with dirt and the sleeper cannot swell up at this point, 60 which would easily make difficult or prevent the removal and replacement of the bolt.

What I claim is:—

1. A rail fastening, comprising in combination, a sole plate having rib-like members 65 extending completely along the sole plate in the direction of the track, between which members the rail can rest, clips for holding down the rail, hammer-headed bolts for holding down said clips, a gap in the middle 70 part of each rib-like member of the width of the shank of said bolts, into which gaps the bolts can be inserted, an aperture in the sole plate below the middle part of each rib-like member into which the bolt heads can be in- 75 serted, the parts of the said members on either side of the gap therein extending over the aperture in the sole plate, and a downwardly projecting lug on the outer limb of each clip, said lug being capable of engag- 80 ing in the aperture in the sole plate and together with the bolt head of almost filling said aperture and having a depth less than that of the sole plate, as and for the purposes set forth. 85

2. A rail fastening, comprising a rail seat having rib-like members, clips capable of bridging said members for holding down the rail, bolts for holding down said clips, an aperture in the rail seat below the middle 90 part of each rib-like member, said aperture being capable of receiving a bolt head and being surrounded by a continuous wall of the material of which the rail seat consists, a gap in the middle part of each rib-like mem- 95 ber of the width of the shank of the bolts into which gaps the bolts can be inserted from the side, the parts of said rib-like members on either side of the gap therein projecting over the aperture in the rail seat, and 100 a lug on the foot of each clip capable of engaging in the aperture in the rail seat, said lug being capable, together with the bolt head, of filling said aperture, as and for the purposes set forth. 105

3. A rail fastening, comprising a rail seat having rib-like members, extending completely along the rail seat in the direction

of the track, between which members the rail can rest, clips capable of bridging said members for holding down the rail, bolts for holding down said clips, an aperture in the 5 rail seat below the middle part of each rib-like member, said aperture being capable of receiving a bolt head and being surrounded by a continuous wall of the material of which the rail seat consists, a gap in the middle part of each rib-like member of the 10 width of the shank of the bolts, into which gaps the bolts can be inserted from the side,

the parts of said rib-like members on either side of the gap therein projecting over the 15 aperture in the rail seat, and a lug on the foot of each clip capable of engaging in the aperture in the rail seat, said lug being capable, together with the bolt head, of filling 20 said aperture, as and for the purposes set forth.

In testimony whereof I have signed my name to this specification.

THEODOR BUCHHOLZ.
